UNITED STATES PATENT OFFICE.

JACOB KAUFMANN, OF PHILADELPHIA, PENNSYLVANIA, ASSIGNEE TO STEEL HEDDLE MANUFACTURING COMPANY, OF PHILADELPHIA, PENNSYLVANIA, A CORPORATION OF PENNSYLVANIA.

LOOM HEDDLE-FRAME.

1,077,719.

Specification of Letters Patent.

Patented Nov. 4, 1913.

Application filed August 29, 1911. Serial No. 646,632.

To all whom it may concern:

Be it known that I, JACOB KAUFMANN, a citizen of the United States, residing at Philadelphia, in the county of Philadelphia, and State of Pennsylvania, have invented 5 certain new and useful Improvements in Loom Heddle-Frames, of which the following is a specification.

My invention relates to loom heddle frames, and it has particular relation to 10 that type of heddle frames in which the end rails are made of relatively narrow material, as for example, of the type shown in my previous Letters Patent No. 980,285, 15 dated Jan. 3, 1911.

As is well known, the heddle frames are mounted in the loom in close relationship to each other and are rapidly reciprocated up and down past each other to form the sheds 20 for the purposes of weaving. It has been found in practice that where the heddle frames are constructed with the end bars made of relatively narrow material that the top and bottom rails frequently foul each 25 other on account of the outer corner of one of the top or bottom rails catching under the inner corner of the top or bottom rail of the adjacent frame. This disadvantage is not found where the heddle frames are made 30 with the end rails of relatively wide material, that is to say, of a width greater than the possible sidewise displacement of the frames with respect to each other, as in this case the faces of the end rails will effectively 35 prevent the fouling.

The principal object, therefore, of my present invention is to provide a simple and efficient means for preventing the fouling of the adjacent heddle frames in the loom 40 where the same are made with the end rails of relatively narrow material.

The nature and characteristic features of my invention will be more readily understood from the following description taken 45 in connection with the accompanying drawings forming part hereof, in which—

Figure 1 is a front elevation of a heddle frame embodying the main features of my present invention; Fig. 2 is an enlarged 50 fragmentary elevation of one of the corners of the frame; Fig. 3 is a transverse section, enlarged, of portions of two adjacent heddle frames in juxtaposition, showing how my improved means acts to prevent fouling of 55 the top and bottom rails of adjacent frames

in a loom; Fig. 4 is a view similar to Fig. 2 but showing a modified form of my invention; Fig. 5 is a perspective view of an element constituting a simple form of device adapted to be attached to a heddle frame for carrying out my invention, the same being shown in its initial form before being mounted in the frame; and Fig. 6 is a perspective view of a form of bracing member 60 for the end rails having wings integrally formed thereon for the purpose of carrying out my invention, the same constituting an alternative form of device for effecting the purpose.

Referring to the drawings, in the particular embodiment of my invention therein shown, the heddle frame comprises the top and bottom horizontal rails 7 and 8 which may be made of the usual wood strips having rounded edges, and these top and bottom rails 7 and 8 are joined at their ends by means of the end rails 9 and 10 preferably made of bar iron, which extend across the end faces of the top and bottom rails 7 and 8 and are bent over and secured on the outer 65 sides of said top and bottom rails as at 11 by means of screws or other suitable fastening means. The end rails 9 and 10 are secured to the top and bottom rails 7 and 8 at the inner corners thereof by means of 70 bracing members 12 which may if desired be constructed and arranged as shown in my previous Letters Patent No. 980,285, or in any other suitable manner. As shown in 75 Figs. 1 and 2 the bracing members 12 comprise plates secured by screws or otherwise to the inner sides of the top and bottom rails at the ends thereof, and having recessed portions for engaging slots in the end rails 9 and 10. The heddle bars 14 and 15 80 upon which the heddles 16 are mounted are carried in the end bars 9 and 10 in any suitable manner, the arrangement being such that the ends of the heddles are arranged a slight distance from the inner sides of the 85 top and bottom rails 7 and 8. Each of the 90 bracing members 12 also serves to maintain a guiding device 17 in place at each inner corner of the heddle frame and as shown the device 17 may comprise a sheet metal 95 member having its side faces bent inwardly and converging in a V shape so as to provide inclined guiding surfaces 18 at each of the inner corners of the frame, so that as the 100 frames are reciprocated, any tendency of 105

110 the frames to move laterally will be resisted by the guiding surfaces 18.

one of the top or bottom rails to catch on the top or bottom rail of an adjacent frame will be counteracted by the inclined guiding surfaces as clearly shown in Fig. 3 of the drawings. As shown in Fig. 5 the guiding device 17 may be made initially of U shape in cross section with straight wings 19 and apertured as at 20 for the passage of the fastening screw of the bracing member 12. After the bracing member is fastened in place by means of the screw 21, the side wings are bent to the V shape as shown in Fig. 3 of the drawings and in dotted lines in Fig. 5.

Instead of employing the separate device 17 for guiding the corners of the adjacent frames as shown in Figs. 1 to 3, the bracing member 12 may be provided with integrally formed converging side wings 22 as clearly shown in Fig. 6 of the drawings. It should also be understood that instead of mounting the guiding devices at the inner corners of the top and bottom rails, the same may be mounted at the outer corners thereof under the turned over ends 11 of the end rails as clearly shown in Fig. 4 of the drawings.

It will be seen that by the foregoing arrangement there is provided a simple and efficient device for preventing fouling of the heddle frames which has heretofore been a great objection to the form of frames made with the end rails of flat relatively narrow metal and having ends bent over and secured on the outer sides of the top and bottom rails. It should be noted that

in the construction of frames where the end rails are thus made of flat metal and bent around as aforesaid that notwithstanding the top and bottom rails may be made with curved edges to prevent fouling at other points along their length, this curvature is destroyed by the bending over of the end rails and the employment of the bracing members which have been found essential in this form of construction. It will, of course, be understood that where the top and bottom rails are made with the flat edges that the device of my present invention may be employed to prevent fouling at other points on the length of the top and bottom rails.

Having thus described the nature and characteristic features of my invention what I claim as new and desire to secure by Letters Patent is—

In a heddle frame, means for preventing fouling of the adjacent frames in the loom comprising a sheet metal device having a flat portion secured to one edge of the horizontal rails and having inclined converging wings extending therefrom.

In testimony whereof, I have hereunto signed my name in the presence of two witnesses.

JACOB KAUFMANN.
